BOX FOR A GIRDLE

Benjamin Murdock, Brooklyn, N. Y.

Application May 6, 1952, Serial No. 19,620

Term of patent 7 years

(Cl. D58—11)

To all whom it may concern:

Be it known that I, Benjamin Murdock, a citizen of the United States, residing at 2406 Avenue P, Brooklyn, State of New York, have invented a new, original, and ornamental Design for a Box for a Girdle, of which the following is a specification, reference being had to the accompanying drawing, forming a part thereof.

Fig. 1 is a front elevation view of a box for a girdle, showing my new design;

Fig. 2 is an elevation view, showing one side thereof;

Fig. 3 is an elevation view, showing the side opposite Fig. 2;

Fig. 4 is a rear elevation view thereof;

Fig. 5 is a top plan view thereof; and

Fig. 6 is an exploded view thereof, showing the cover portion removed from the box.

I claim:

The ornamental design for a box for a girdle, as shown.

BENJAMIN MURDOCK.
